ARCH BRICK

John P. Neff, East Orange, N. J., assignor to
American Arch Company, New York, N. Y., a
corporation of Delaware

Application August 17, 1931, Serial No. 557,607

4 Claims. (Cl. 110—87)

This invention relates to locomotive arch brick and is particularly concerned with that type of brick which may be defined as the "lean-to" type of brick, i. e., a brick which is supported at its lower end upon a supporting member of some kind, generally a circulation tube, and which inclines upwardly and outwardly from said support to lean against an adjacent wall in a locomotive fire box. Bricks of this character are very common in present practice between the outermost circulation tubes and the side sheets of the fire box, and for illustrative purposes the present invention is described as embodied in a side brick for locomotive fire box arches. It should be understood, however, that a brick embodying the present invention might be equally well employed between a supporting member such as a circulation tube and the adjacent side wall of an internal water leg, or, indeed, in any location where similar conditions exist.

The principal object of the invention may be said to reside in the provision of a brick of the character described which can be inverted and which when inverted is adapted to span unequal distances between points of support so as to materially reduce the number of brick patterns or sizes which may be necessary in making an installation. For example, many modern locomotives have fire boxes in which the side sheets taper inwardly and upwardly as well as forwardly and outwardly so that the space between the side sheets at the mud ring is greater than the space at the crown sheet, and the distance between sheets is greater at the flue sheet than it is at the back sheet, in which latter sheet is located the customary fire door opening. The amount of taper in either case is not always very pronounced, but nevertheless is generally sufficient to require the use of a good many patterns or sizes of side bricks. As stated, it is one of the principal objects of the invention to provide a construction which will reduce the number of patterns necessary to make an installation.

A further object of the invention is to provide a brick of the character described which, when inverted, will span unequal distances between points of support and which, at the same time, is so constructed that inversion of the brick will not substantially alter the incline of either the top or the bottom face of the brick. In other words, a substantially uniform arch setting can be obtained with my improved brick with practically fifty percent fewer brick sizes than would ordinarily be necessary.

It is also an object of the present invention to

provide a brick having the foregoing characteristics which will, at the same time, be extremely rugged in character and not easily broken in service.

How the foregoing objects, together with such other objects as are incident to the invention or which may appear hereinafter, are attained, is illustrated in the preferred form in the accompanying drawings, wherein—

Figure 1 is a cross section through a standard locomotive fire box arch showing my improved type of "lean-to" brick as applied to the two outermost circulation tubes of a series of four tubes in position to span the distance from such tubes to the side sheets.

Figure 2 is an enlarged side elevation of one embodiment of my improved brick illustrating certain details of the construction, the view being dimensioned and drawn to scale.

Figure 3 is a comparative view illustrating my improved brick in both of its positions in order to show the manner in which it spans unequal distances between points of support; and

Figure 4 is a composite view showing my improved brick in both of its positions, one position being superimposed over the other, and one being shown in full lines and the other in dotted lines in order to illustrate the fact that my improved construction does not substantially alter the incline of the top and bottom faces of the brick when inverted to span unequal distances between points of support.

In Figure 1 is shown a cross section through a locomotive fire box arch spanning the distance between the side sheets 5, the arch being supported upon a series of four circulation tubes 6 with three rows of M or middle bricks 7 and a row of "lean-to" side bricks 8 at each side.

Figure 2 illustrates in detail the specific construction of my improved brick, but I wish it to be distinctly understood that it is not necessary to limit the present invention to a brick of the exact size or shape indicated by the dimension figures, such figures being placed upon the drawings simply as a guide to show one way in which a brick of this character may be constructed in order to incorporate the features of the present invention.

By examining the drawings, it will be seen that my improved "lean-to" brick is preferably provided at its lower end with a symmetrical support engaging surface 9 which, in the present embodiment, takes the form of a socket of slightly larger radius than the radius of the tubes 6 upon which its rests. The opposite or upper end of the brick is

of blunt nose-like construction which is asymmetrical with respect to the longitudinal plane 10 (see particularly Figure 2) which divides the brick into two substantially equal parts, the plane 10 passing through the axis of the tube 6. In other words, the nose is somewhat off center.

The portion 11 of the blunt end having the smaller radius indicated in Figure 2 lies to one side of the plane 10 (above the plane in Figure 2), and the portion 12 having the greater radius to the other side of the plane 10 (below the plane in Figure 2).

By examining Figures 3 and 4 it will, therefore, be seen that the bulk of the nose end of the brick 15 in one of its positions lies above the plane 10 and in the other position below the plane 10. When it lies above, the brick will span the lesser distance 13; and when it lies below, the greater distance 14. However, as shown by the composite view of Figure 4, the construction of the brick is of such a nature as not to affect or alter 20 to any substantial degree the general direction of the incline of the upper and lower faces of the brick regardless of the position in which it is placed. This is an important feature of the invention because it makes possible a substantially uniform setting of the bricks, or, stated in other words, an arch application having substantially 25 uniform facings.

30 The advantages which flow from a brick embodying my improved characteristics will be more fully appreciated from the following: In present practice with side bricks of the types which are now customary, the workmen who make the installations are accustomed to chip the side bricks in order to line them up evenly, with the result that quite frequently the front bricks of an arch, where the fire box is wider than it is at the back, are set at an angle which is considerably less than the desired angle so that they have a tendency to wedge the arch tubes out of alignment. In other words, the workmen, instead of using the necessary number of patterns to build up an arch having substantially uniform top and bottom 45 faces, adopt the expedient of chipping away portions of the brick in order to build up an installation which has substantially uniform top and bottom faces.

With the present invention, however, this difficulty is largely overcome because the workmen, by simply inverting the brick, can build up an arch which has substantially uniform top and bottom faces. Therefore, as the front of the fire box is approached the angle at which the brick is inclined upwardly will not become so small as to create a tendency for the brick to wedge down between the tube and the side sheet and force the tube out of alignment.

As shown in Fig. 2, the two faces of the brick 60 are slightly curved upon rather large radii, the radius on one side, however, being smaller than

that on the other. In the present instance, radii of 60 inches and 84 inches respectively are used. The curve of smaller radius merges into the blunt portion 11 and that of larger radius into the surface 12. It will be understood, of course, that the particular configuration of the brick shown in the present embodiment is not essential to the invention as many other sizes and shapes could be designed any one of which may be made so as to incorporate the features of the present invention. In other words, the particular size and shape illustrated, while representing a preferred embodiment of the invention, is not to be construed as limiting the scope of the appended claims.

It will be seen that the brick is of extremely rugged construction and that substantially no strength is sacrificed by constructing the blunt nose-like end of the brick in the manner illustrated. Breakage, therefore, is not liable to occur and the brick is at all times firmly seated in its position, regardless of which face is uppermost.

What I claim is:—

1. An invertible brick of the "lean-to" type 100 having its upper end formed as a rounded nose of asymmetrical curvature and with the opposite faces struck upon radii of unequal length.

2. An invertible brick of the "lean-to" type 105 having its upper end formed as a rounded nose of asymmetrical curvature and with the opposite faces struck upon radii of unequal length, the surface of lesser radius merging with the nose in its region of sharper curvature, and the surface of greater radius merging with the nose in its 110 region of lesser curvature.

3. An invertible brick of the "lean-to" type characterized by the fact that its upper or leaning end is of asymmetrical form to provide a nose-like projection, having a portion adjacent one 115 face of the brick which projects outwardly endwise of the brick a greater distance than the portion adjacent the opposite face of the brick whereby the brick when inverted will span unequal distances between points of support. 120

4. A side brick for locomotive fire box arches of the type which is adapted to rest at its inner end upon a circulation member and to incline upwardly and outwardly toward and to lean against the side sheet of the box, said brick having a circulation member engaging face at its inner end and an asymmetrical side sheet contacting nose at the other end, and said nose having a portion adjacent one face of the brick which projects outwardly endwise of the brick a greater 125 distance than the portion adjacent the opposite face of the brick whereby the brick when inverted will span unequal distances between points of support. 130
